UNITED STATES PATENT OFFICE

2,409,737

CHIP EJECTOR FOR HEEL SEAT FITTING MACHINES

Thomas Baggott Clarke and Frederick William Henry Williams, Leicester, England, assignors to United Shoe Machinery Corporation, Flemington, N. J., a corporation of New Jersey

Application March 8, 1945, Serial No. 581,585
In Great Britain June 6, 1944

7 Claims. (Cl. 12—31.5)

1

This invention relates to machines for use in the manufacture of shoes and particularly to improved chip ejector mechanism adapted for use, for example, in heel seat fitting machines.

In order to remove chips of surplus outsole material from crease plates of heel seat fitting machines of the general type disclosed in United States Letters Patent No. 2,215,524, granted September 24, 1940, on an application filed in the name of George Hazelton, for example, ejectors of various constructions have been proposed. The chips are commonly forced over the front edges of the crease plate by the ejector and preferably fall into a container.

The rear ends of chips left on the crease plate after the completion of the heel seat fitting operation are located in different positions lengthwise of said plate. The chip should be moved forward by the ejector with the proper amount of force to cause it to clear the forward edges of the crease plate and to fall into the container. Such force, however, should not be so great that the chip is thrown past the container and onto the floor. Many ejectors commonly in use rely upon springs for their actuation, and with such ejectors it has been proposed to provide dashpots operating in opposition to the springs in order to insure that the chip shall be so operated upon that it is removed from the crease plate and falls into the container. It has been found, however, that the dashpot adds considerably to the expense and service of the ejector. Moreover, the action of the dashpot when not properly adjusted tends to slow up the production of the machine.

It is an object of the present invention to provide a simple, spring-actuated ejector by the use of which the above-mentioned chips may be quickly and effectively removed from crease plates of heel seat fitting machines of the general type referred to above, with the proper amount of force to deposit them in a container.

With the above object in view and in accordance with a feature of the present invention there is provided, in a heel seat fitting machine, a movable spring-energized actuator having a fixed driving stroke, a reciprocatory ejector bar, positive driving means between the actuator and the ejector bar, mechanism comprising a cam for rendering said driving means inoperative to cause chip ejecting movement of said bar to cease, and means whereby said cam may be moved into different adjusted positions in order to cause the bar to be disconnected from the actuator at different portions of the driving stroke of the actuator.

2

The illustrative ejector, which is effective in its operation and is of simple construction, will be hereinafter described in connection with the accompanying drawings, in which

Fig. 1 is a side view, partly in section, of the heel seat fitting machine disclosed in said Letters Patent No. 2,215,524, provided with my novel ejector mechanism;

Figs. 2, 3 and 4 are side, rear and plan views, respectively, of the ejector in its cocked position ready to be tripped preparatory to ejecting a chip from the machine;

Fig. 5 is a view corresponding to Fig. 2 showing the ejector prior to being cocked; and

Fig. 6 is an exploded view showing, in perspective, the various parts of the ejector in its cocked position.

As illustrated, the ejector comprises a U-shaped bar 20 having at its closed end a T-shaped head 22 which is moved forward over a multipart crease plate 24 (Figs. 1, 2, 4 and 5) of the heel seat fitting machine disclosed in the above-mentioned Letters Patent No. 2,215,524, for example, in order to slide a U-shaped chip 26 (Fig. 4), trimmed from the heel seat portion 25 (Fig. 1) of an attached outsole of a shoe 27 and lying upon the crease plate, over the forward edges 28 (Figs. 1 and 4) of the crease plate and into a container (not shown) arranged at the front of the machine. Since the present invention is directed primarily to the ejector, only those parts of the heel seat fitting machine which actively co-operate with said ejector will be disclosed. It will be understood that the ejector, slightly modified if desirable, can be readily incorporated in various types of heel seat fitting machines now in use.

Secured by screws 30 to a head casting 32 of the main frame of the above machine is a bracket 34 having secured to it by a setscrew 36 a fulcrum pin 38 upon which are pivoted bell-crank levers 40, 42 (Figs. 4 and 6), respectively, and an adjustable cam 44. As will appear later, the bell-crank lever 40, which may be referred to as a driving lever or an actuator, is latched in the cocked position shown in Figs. 2 to 4 and 6, to operate, when released through mechanism to be later described, the bell-crank lever 42, which may be referred to as a driven lever and comprises a depending arm 46 bifurcations 48 of which are arranged at opposite sides of a screw 50 (Figs. 1 and 3) utilized to adjust a heel seat reducing knife 51 (Fig. 1) relatively to a knife carrier 52 mounted for forward and rearward movement in a guide-way 54 (Fig. 3) of the machine frame.

55 The rear end of the bifurcated bar 20 is mount-

ed upon studs 56 secured to the lower ends of the bifurcations 48 of the depending arm 46, the bar being held on the studs by a cotter pin 58 (Figs. 3, 4 and 6). Secured to a forward arm 60 of the bell-crank lever 42 and to a depending arm 62 of the bell-crank lever 40 are studs 64, 66, respectively, which are fixed to opposite ends of a tension spring 68 and are continuously urged toward each other by said spring. The bell-crank lever 40 is constantly urged clockwise, as viewed in Figs. 1, 2, 5 and 6, about the fulcrum pin 38 by a strong spring 70 the lower end of which is connected to a forward arm 72 of the bell-crank lever 40 and the upper end of which is attached to a stud 74 (Figs. 1 and 2) secured to the head casting 32 of the machine.

While the machine is idle and during the major portion of the operation of the machine, the depending arm 62 of the bell-crank lever 40 is forced against a spring-resisted buffer stop 76 mounted on the bracket 34, the arm 60 of the bell-crank lever 42 at such time being held in its retracted idle position by the spring 68, said position being determined by the engagement of the forward arm 60 of said lever 42 with a spring-resisted buffer stop 80 also mounted upon the bracket 34. After the heel seat portion 25 (Fig. 1) of the attached outsole of the shoe 27 has been fitted, the depending arm 62 of the bell-crank lever 40 is moved rearward away from the spring buffer stop 76 by a shoulder 82 (Figs. 2, 5 and 6) of a latch 84 which is mounted upon a fulcrum pin 86 carried by an upstanding block 88 secured to the knife carrier 52. It will be understood that as the knife carrier 52, together with the block 88, moves rearward the latch 84 is in a raised position, since at such time it is held in engagement with a stop face 90 of the block by a spring-pressed plunger 92 and therefore the shoulder 82 of the latch will contact the arm 62 during retraction of the knife carrier. As explained later, almost immediately after the latch 84 has been retracted it is tripped by a rod 94 to enable the depending arm 62 to move forward under spring action against the spring buffer stop 76 to cause, through mechanism which will be hereinafter described, the chip 26 to be ejected, the machine then being idle. Accordingly, when the machine is idle, the knife carrier 52 is in its retracted position, shown in Fig. 5, the latch 84 at such time being depressed against the action of the spring-pressed plunger 92 (Figs. 2 and 6) away from the stop face 90 of the block 88 by the rod 94, which is actuated by mechanism hereinafter described.

As the knife carrier 52 moves rearward after the heel seat fitting operation, the shoulder 82 of the latch 84 forces the depending arm 62 of the actuator rearward against the action of the springs 68, 70 and, after reaching the position shown in Figs. 2 and 6, comes to rest, the rear end of the latch then being positioned beneath but spaced from the rod 94 which is pivoted at its upper end to a bent lever 96. The lever 96 is adjustably secured to a treadle-controlled arm 98 through which a multipart bulger 99 depresses the heel seat portion of the sole of the shoe through a U-shaped opening 100 (Fig. 4) of the crease plate 24. The rod 94 passes through a vertical bore 102 in a lateral lug 104 of the bracket 34, the arrangement being such that when the treadle-operated arm 98 is swung clockwise as viewed in Fig. 2 upon release of a treadle (not shown) by the operator, the rod swings the latch 84 clockwise, with the result that the depending arm 62, which at that time, as will appear later,

is coupled to or connected for positive movement with the bell-crank lever 42, swings clockwise from its position shown in Fig. 2 under the action of the springs 68, 70 into engagement with the spring buffer stop 76.

Mounted for swinging movement in a bore of a forward projection of the depending arm 62 is a pin 106 (Figs. 2, 3, 5 and 6) to which is secured at opposite sides of the arm a pawl 108 (Fig. 6). The pawl 108 is constantly urged in a clockwise direction (Fig. 6) by a spring 112 upper and lower ends of which are attached to studs 114, 116, respectively, secured to the pawl and to the depending arm 62. Movement of the pawl 108 clockwise, as viewed in Figs. 1, 2 and 5, by the action of the tension spring 112 is limited by the engagement of a roll 118 carried by the pawl with an eccentric face 119 of the cam 44. The face 119 of the cam 44 is so shaped and arranged that as the depending arm 62, which may be referred to as a pawl carrying arm, reaches approximately its cocked position, shown in Fig. 2, the pawl is permitted to move into a notch or against a shoulder 120 (Fig. 6) formed in the lower face of the forward arm 60 of the bell-crank lever 42. When the latch 84 is depressed by the rod 94, the depending arm 62 of the bell-crank lever 40 swings forward, rotating with it through the positive pawl and shoulder driving connection above described the bell-crank lever 42, with the result that the T-shaped head 22 of the bifurcated ejector bar 20 is moved forward against the U-shaped chip 26 left upon the crease plate 24, with sufficient force to slide the chip over the forward edges 28 of the plate and into the above-mentioned container (not shown) at the front of the machine.

The cam 44 (Fig. 6) has secured to it a threaded stud 122 which fits into an arcuate slot 124 of the bracket 34 and is clamped in different operative positions to the bracket by a nut 126. When the latch 84 is tripped, the bell-crank lever 42 moves with the bell-crank lever 40 until the pawl 108 carried by the depending arm 62 of the bell-crank lever 40 is swung out of engagement with the shoulder 120 of the arm 60 of the bell-crank lever 42 as the result of the action of the eccentric face 119 of the cam 44 upon the roll 118. When the driving connection between the pawl carrying lever 62 and the arm 60 is broken, the driven bell-crank lever 42 operated upon by the tension spring 68 swings in a counterclockwise direction, as viewed in Figs. 2 and 5, until the arm 60 of said lever engages the spring buffer stop 80, the pawl carrying lever 62 moving clockwise until it engages the spring buffer stop 76.

It will be apparent that by setting the cam 44 in different adjusted positions upon the fulcrum pin 38 it is possible to regulate the amount of forward travel of the bifurcated ejector bar 20 and accordingly the amount of force applied against the chip 26 left upon the crease plate 24, said amount being sufficient to move the chip over the forward edges 28 of the crease plate and into but not beyond the container.

Having described our invention, what we claim as new and desire to secure by Letters Patent of the United States is:

1. In a heel seat fitting machine, a movable spring-energized actuator having a fixed driving stroke, a reciprocatory ejector bar movable to remove a chip from the machine, positive driving means between the actuator and the ejector bar, mechanism comprising a cam for rendering said driving means inoperative to cause chip ejecting movement of said bar to cease, and means

for setting said cam in different adjusted positions in order to cause the actuator to be disconnected from the bar at different portions of the driving stroke of the actuator.

2. In a heel seat fitting machine, an ejector bar, a lever for operating said bar, a stop, a spring for constantly urging the lever to an idle position against the stop, a spring-energized actuator having a constant driving stroke, a coupling for positively moving said lever in response to movement of the actuator, and means for rendering inoperative the coupling between the actuator and the lever at different stages of the driving stroke of the actuator.

3. In a heel seat fitting machine, a reciprocable chip ejector bar, a lever pivoted to the ejector bar, a spring for constantly urging the lever to a retracted idle position, an actuator, a stop, a spring for urging the actuator in one direction against the stop, means for causing the lever to be moved positively in response to spring-energized movement of the actuator toward said stop, and mechanism comprising a cam for rendering said means inoperative at a predetermined stage of the spring-energized movement of the actuator to break the driving connection between the lever and the actuator, said lever when its driving connection with the actuator is broken being moved back to its retracted idle position by its associated spring.

4. In a heel seat fitting machine, a reciprocable ejector bar, a carrier for a heel seat reducing knife, resilient means for constantly urging the ejector bar to a retracted idle position, an actuator, a stop, a spring for constantly urging the actuator in one direction against the stop, a latch movable in response to movement of the knife carrier for moving the actuator to a cocked position against the action of the spring, means for tripping the latch to permit the cocked actuator to move under the action of the spring toward said stop, and a driving coupling constructed and arranged to cause the ejector bar positively to be moved away from its retracted idle position in response to spring-energized movement of the actuator, said coupling being rendered inoperative after the actuator has moved a predetermined distance from its cocked position thereby permitting the ejector bar to move back to its retracted idle position under the action of said resilient means.

5. In a heel seat fitting machine, a chip ejector bar, a lever for operating said bar, an actuator, a spring, means for moving the actuator to a cocked position against the action of the spring, a pawl carried by the actuator, a shoulder which is formed on said lever and is constructed and arranged to be engaged by said pawl when the actuator is approximately in its cocked position, means for releasing the actuator from its cocked position to permit it to be moved by said spring thereby causing the lever to be moved through

the pawl away from an idle retracted position, and cam-operated means for moving the pawl away from said shoulder of the lever at a predetermined stage of the movement of the actuator away from its cocked position to cause the lever to be disconnected from the actuator and to be permitted to move back to its idle retracted position.

6. In a heel seat fitting machine, an actuator, a reciprocatory ejector bar, a lever operatively connected to the bar, a spring which connects the actuator to the lever and is constructed and arranged constantly to urge the ejector bar to an idle retracted position, a stop, a second spring co-operating with the first-named spring in urging the actuator to an idle position against the stop, means for moving the actuator to a cocked position against the action of said springs, means comprising a latch for retaining the actuator in its cocked position, means for causing the lever to be moved positively in response to movement of the actuator away from its cocked position and thus to cause said lever and accordingly the ejector bar to remove from the machine a chip trimmed from the heel seat portion of the outside of a shoe, and means for disconnecting said lever from the actuator at a predetermined stage of the stroke of the actuator toward said stop to cause ejecting movement of said bar to cease and to permit said bar to return to its idle retracted position under the action of the first-named spring.

7. In a heel seat fitting machine, an ejector bar, a lever operatively connected to the bar, an actuator, a pair of stops, a tension spring which connects the lever and the actuator and is constructed and arranged constantly to urge the lever and the actuator to idle positions against the respective stops, another tension spring constructed and arranged constantly to urge the actuator with considerable force against its associated stop, a carrier for a heel seat reducing knife, a latch mounted upon said carrier and constructed and arranged upon retractive movement of the carrier to move the actuator against the action of said springs to a cocked position away from its associated stop, a coupling for securing the lever to the actuator when said actuator has been moved approximately to its cocked position, means for tripping the latch when the actuator is in its cocked position to permit the then spring-energized actuator to move toward the stop thereby positively moving with it the lever and the ejector bar, and means comprising an adjustable cam for breaking the coupling between the actuator and the lever at a variable but predetermined stage of the spring-energized stroke of the actuator to vary the extent of ejecting movement of said bar.

60 THOMAS BAGGOTT CLARKE.
FREDERICK WILLIAM HENRY WILLIAMS.
